UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,356,643.

Specification of Letters Patent. Patented Oct. 26, 1920.

Application filed December 27, 1918. Serial No. 268,446.

To all whom it may concern:

Be it known that I, JAMES L. MCQUARRIE, a citizen of the United States, residing at Montclair, in the county of Essex, State of New Jersey, have invented certain new and useful Improvements in Telephone Systems, of which the following is a full, clear, concise, and exact description.

This invention relates to improvement in automatic telephone exchange systems, and has particular reference to a circuit arrangement therefor.

It has been customary in automatic systems of known construction to send impulses by interrupting the line circuit at the substation apparatus, whereby circuit changes are effected at a selector switch for operating the same. In arrangements of this character the possibility of an incorrect setting of the switch and consequent mutilation of a call is occasioned by accidental depression of the switchhook when removing the receiver therefrom, which results in an unintentional interruption of the line circuit and the transmission of a false impulse.

An object of the present invention is to provide means whereby a selector switch will only respond to variations of current in the line circuit produced by the actuation of an impulse sending device, and which will prevent operation of the switch should the line circuit be completely interrupted, as by an accidental depression of the switchhook.

The inventive idea involved is capable of receiving a variety of expressions one of which, for the purpose of illustrating the invention, is shown in the accompanying drawing; but it is to be expressly understood that said drawing is employed merely for the purpose of facilitating the description of the invention as a whole, and not to define the limits thereof, reference being had to the appended claims for this purpose.

The figure illustrates diagrammatically a calling substation line and a selector switch embodying the features of this invention.

In the drawing, the subscriber's substation apparatus A may be of the usual construction including the switchhook which is designed to close and interrupt the substation line circuit consisting of limbs 1 and 2. An impulse sending device B of any desired construction is also associated with the substation apparatus, and includes a normally opened contact 3 which is closed upon op-

eration of the sending device to shunt said apparatus. Another normally closed contact 4 is provided at the sending device B for bridging a resistance 5 in series with the line circuit.

A primary switch indicated at C and which may be of any known construction is employed for connecting the line circuit to the selector switch D, which includes two line relays 6 and 7 employed for controlling the operation thereof. Both relays 6 and 7 are energized upon closing of the line circuit by the switchhook at substation A, and will release, should said line circuit be interrupted by an accidental depression of said switchhook and thereby prevent any operation of the selector switch. Upon manipulation of the impulse sending device B, contact 4 will be opened in response to the impulses, and resistance 5 will be placed in series with the line circuit, and the electrical condition thereof thereby changed at each transmission of an impulse. Relay 7 will remain energized during the manipulation of the sending device, but relay 6 is so adjusted as to respond to the variations in current and will release each time resistance 5 is introduced in the line circuit.

It is believed that the invention will now be best understood through the following detailed description of the operation.

When the subscriber at substation A removes his receiver from its switchhook, primary switch C is operated in a manner well known in the art to step its brushes onto the terminals of a trunk leading to an idle selector switch D. A circuit will then be closed extending from grounded battery, left winding of marginal relay 6, left winding of relay 7, side switch wiper 8 in its first position, limb 1 of the subscriber's line, substation apparatus A, contact 4 and its associated spring, side switch wiper 9 in its first position, right winding of relay 7, and right winding of relay 6 to ground. Relays 6 and 7 are energized and establish a circuit for the slow-to-release relay 10, extending from grounded battery, winding of said relay 10, front contact and armature of relay 6, front contact and armature of relay 7, to ground. Relay 10 in attracting its armature, prepares a circuit for slow-to-release relay 11 which is closed upon transmission of the first impulse from sending device B.

In response to each impulse transmitted

by said device, contact 4 is opened, and the line circuit will extend through resistance 5. This change in current will not affect relay 7, as previously described, but the increase in resistance will cause relay 6 to release and slow-to-release relay 11 will immediately become energized over a circuit extending from grounded battery, winding of relay 11, front contact and inner armature of relay 10, back contact and armature of relay 6, front contact and armature of relay 7, to ground. Relays 10 and 11 remain energized during the transmission of impulses. A circuit will also be closed for primary stepping magnet 12 extending from grounded battery, winding of said magnet, side switch wiper 13 in its first position, front contact and inner armature of relay 10, back contact and armature of relay 6, front contact and armature of relay 7, to ground. Stepping magnet 12 will continue to operate in response to impulses transmitted and thus step the brushes of selector switch A to the desired group of terminals. On the first step of switch D off-normal contact 14 is closed. Energization of slow-to-release relay 11 operates escape magnet 15 over a circuit extending from grounded battery, winding of said magnet, side switch wiper 16 in its first position, front contact and armature of relay 11, to ground.

At the termination of the first set of impulses, contact 4 will close and short circuit resistance 5 and relays 6 and 7 will both remain energized. This condition of relay 6 will break the circuit for slow-to-release relay 11 at the back contact of the armature of said relay 6, and upon deenergization of relay 11, escape magnet 15 will release and cause the side switch wipers to move into their second positions. A circuit for the secondary stepping magnet 17 is immediately established which extends from grounded battery, winding of magnet 17, armature and back contact thereof, side switch wiper 18 in its second position, back contact and armature of escape magnet 15, to ground. Magnet 17, being self-interrupting, will step the brushes of switch D in their trunk hunting operation. The idle condition of the terminals over which brushes of the switch pass is denoted by ground, and upon being stepped onto the test terminal having such condition, a circuit will be closed for escape magnet 15, extending from grounded battery, winding of said magnet, side switch wiper 16 in its second position, test brush 19 and its associated terminal, to ground at the next succeeding selector switch (not shown). Energization of magnet 15 breaks the circuit for stepping magnet 17 and the brushes of the switch will come to rest upon the set of terminals leading to the idle selector.

The several side switch wipers are also moved to their third positions upon energization of escape magnet 15, thus causing the line circuit to be extended to the next selector and relays 6 and 7 to release. The sending device B may now be again operated and in accordance with any well-known practice the connection between the substation A and a called line will be established.

If, before the sending device B is initially manipulated to operate selector switch D, the switchhook at substation apparatus A should be accidentally depressed, it will be apparent that the line circuit will be completely interrupted and relays 6 and 7 will both release. Consequently any false impulse, due to such depression of the switchhook which would otherwise be transmitted to the selector switch, will be prevented from so doing.

Should the subscriber at substation A replace his receiver before the side switch wipers of selector D have moved into their third positions, relays 6 and 7 will again release and a circuit will thereby be established for release magnet 20, extending from grounded battery, winding of said magnet, off-normal contact 14, side switch wiper 21 in its first or second positions, back contact and outer armature of slow-to-release relay 10 which becomes deenergized when relay 7 releases, back contact and armature of relay 7, to ground. Upon energization of release magnet 20 a holding circuit is also established therefor, extending from grounded battery, winding of said magnet, off-normal contact 14, armature and front contact of magnet 20, to ground, and said magnet continues to operate to return switch D to normal position, whereupon the holding circuit for magnet 20 is opened at off-normal contact 14.

At the termination of a conversation between the subscriber at substation A and a called subscriber, hanging up of the receiver at the called substation will place ground upon the terminal engaged by test brush 19, and a circuit will be established for release magnet 20 extending from grounded battery winding of said magnet, off-normal contact 14, side switch wiper 21 in its third position, and brush 19 to ground through said test terminal. The previously described holding circuit for release magnet 20 will also be established, and brushes of the switch and side switch wipers will be returned to normal. When side switch wiper 22 returns to its first position, a ground will be found which may be utilized for releasing primary switch C and which extends through the armature of relay 7, back contact thereof, outer armature and back contact of relay 10, and side switch wiper 22 in its first position. This ground is also employed to indicate the idle condition of selector switch 130

D after the same has been returned to normal.

What is claimed is:

In a telephone exchange system a calling line, a called line, a selector switch for extending said calling line toward said called line, primary and secondary stepping magnets for said switch, an escape magnet for controlling the operation of said secondary magnet, a release magnet for said switch, two devices for changing the electrical con-

dition of said calling line, and electromagnetic means under the sole control of one of said devices for controlling said primary and secondary magnets and under the control of both of the devices for causing the operation of said release magnet. ¹⁵

In witness whereof, I hereunto subscribe my name this 24th day of December A. D., 1918.

JAMES L. McQUARRIE.
